CLAIM

The ornamental design for a display system screen or portion thereof with a graphical user interface for mixed reality, as shown and described.

DESCRIPTION

FIG. 1 is a front view of a first image for a display system screen or portion thereof with a graphical user interface for mixed reality, showing a first embodiment of the claimed design;

FIG. 2 is a front view of a second image for a display system screen or portion thereof with a graphical user interface for mixed reality;

FIG. 3 is a front view of a third image for a display system screen or portion thereof with a graphical user interface for mixed reality;

FIG. 4 is a front view of a fourth image for a display system screen or portion thereof with a graphical user interface for mixed reality;

FIG. 5 is a front view of a first image for a display system screen or portion thereof with a graphical user interface for mixed reality, showing a second embodiment of the claimed design;

FIG. 6 is a front view of a second image for a display system screen or portion thereof with a graphical user interface for mixed reality;

FIG. 7 is a front view of a third image for a display system screen or portion thereof with a graphical user interface for mixed reality; and,

FIG. 8 is a front view of a fourth image for a display system screen or portion thereof with a graphical user interface for mixed reality.

The appearance of the transitional image sequentially transitions between the images shown in FIGS. 1-4, and 5-8, respectively. The process or period in which one image transitions to another image forms no part of the claimed design.

(Continued)

The outermost long dashed double-short dashed broken lines show the display system screen or portion thereof. The dashed broken lines within the display system screen show portions of the graphical user interface. The dotted broken line within the display system screen shows the mixed reality environment in which the design is used. The broken line outside of the display system screen shows environmental subject matter. None of the broken line subject matter forms part of the claimed design.

The appearance of the images that sequentially transitions from the first image to the fourth image shows a display system screen or portion thereof with a third embodiment of a graphical user interface for mixed reality.

The appearance of the images that sequentially transitions from the fifth image to the eighth image shows a display system screen or portion thereof with a fourth embodiment of a graphical user interface for mixed reality.

The process or period in which one image transitions to another image forms no part of the claimed design. The outermost long dashed double-short dashed broken lines show the display system screen or portion thereof. The dashed broken lines within the display system screen show portions of the graphical user interface. The dotted broken lines within the display system screen show the mixed reality environment in which the design is used. The broken lines outside of the display system screen show environmental subject matter. None of the broken line subject matter forms part of the claimed design.
